US00D933710S

(12) **United States Design Patent** (10) Patent No.: **US D933,710 S**
(45) Date of Patent: **** Oct. 19, 2021**

(54) **DISPLAY SCREEN WITH ICON**

- (71) Applicant: **Google LLC**, Mountain View, CA (US)
(72) Inventor: **Sehee Lee**, Brooklyn, NY (US)
(73) Assignee: **GOOGLE LLC**, Mountain View, CA (US)
(**) Term: **15 Years**
(21) Appl. No.: **29/722,872**
(22) Filed: **Feb. 3, 2020**

Related U.S. Application Data

- (63) Continuation of application No. 29/695,509, filed on Jun. 19, 2019, now abandoned, which is a continuation of application No. 29/643,554, filed on Apr. 10, 2018, now abandoned.
